UNITED STATES PATENT OFFICE.

TOWNSON HAND, OF ORLANDO, FLORIDA.

SHOE-HEEL.

1,295,892.

Specification of Letters Patent. Patented Mar. 4, 1919.

Application filed August 28, 1918. Serial No. 251,800.

To all whom it may concern:

Be it known that I, TOWNSON HAND, a citizen of the United States, and a resident of Orlando, in the county of Orange and State of Florida, have invented a new and useful Improvement in Shoe-Heels, of which the following is a specification.

My present invention relates generally to shoe heels and particularly to cushion heels, my object being the provision of a cushion heel which will be durable and lasting and which will wear evenly and uniformly during use both for the purpose of increasing its length of life and preserving generally the same appearance throughout such life.

My invention is applicable with equal facility to shoes for both men and women and with but slight modification, such as I will later describe.

In the accompanying drawings illustrating my present invention,

Figure 1 is a side view illustrating the practical application of my invention to the heel of women's shoes.

Fig. 2 is the vertical section taken substantially on the line 2—2 of Fig. 1.

Fig. 3 is a top plan view of the lower bearing plate.

Fig. 4 is a bottom plan view of the upper bearing plate.

Fig. 5 is a bottom plan view of the tread plate.

Fig. 6 is a vertical section through a construction as applied to men's shoes.

Fig. 7 is a bottom plan view of the upper bearing plate of Fig. 6.

Fig. 8 is a bottom plan view of the tread plate of Fig. 6, and

Fig. 9 is a perspective view of the vertical stud or connecting member of Fig. 6.

Referring now to these figures and particularly to Figs. 1 to 5 inclusive, my invention proposes a construction including a lower tread plate, 10, upper and lower bearing plates, 11 and 12 respectively, and a cushion member, 13, which is interposed and held between the tread plate, 10, and the lower bearing plate, 12.

The bearing plates 11 and 12 have their inner opposing faces provided with annular flanges, 14 and 15 respectively, which are disposed in abutting relation so as to thus reduce their contacting areas and consequently the friction therebetween. Both

of these bearing plates have circular openings, 16, and in addition thereto the upper bearing plate, 16, has a series of small openings, 17, around its circular opening for the reception of nails and like fastening members, 18, which are driven upwardly into the upper solid portion, 19, of the shoe heel rigidly attached in a suitable manner to the shoe, 20, as seen in Fig. 1.

The tread plate, 10, has a circular opening, 21, and is provided with a counter-bore 65 upon its lower surface by virtue of a depending annular flange, 22, and a single connecting member, 23, in the present instance in the form of a screw, extends upwardly through the opening, 21, of the tread plate, 70 its lower head, 24, being counter-sunk in the lower face of the tread plate and its upper portion being extended through the circular opening, 16, of the two bearing plates as well as through a circular opening of the 75 cushion, 13, and finally into the upper rigid portion, 19, of the shoe heel so that with the upper bearing plate, 11, securely fastened as previously described, the lower bearing plate together with the tread plate and the cushion 80 are rotatable as a unit upon the connecting member or stud, 23, so that the lower face of the tread plate, 10, will be subjected to uniform, even wear so as to both increase its life and preserve its appearance during its life. 85

As applied to men's shoes my invention is but slightly different from the above construction, upper and lower tread plates, 11^a and 12^a, being utilized with engaging annular flanges, 14^a and 15^a, and with a lower 90 tread plate, 10^a, with a dependent annular flange, 22^a, a cushion, 13^a, being interposed between the tread plate, 10^a, and the lower bearing plate, 12^a, and receiving the lower headed end, 24^a, of the connecting member 95 or stud, 23^a.

The upper bearing plate, 11^a, is however provided with a depending hub or sleeve, 11^b, which extends downwardly through the lower bearing plate, 12^a, and into the upwardly projecting hub or sleeve, 10^b, of the bearing plate, and the upper end of the hub or sleeve 11^b, which is internally threaded to receive the upper threaded end of the connecting member or stud, 23^a, also has longitudinal slots arranged with a line as to longitudinal slots, 23^b, of the connecting member or stud as seen in Fig. 9, for the recep-

tion of a U-shaped locking member, 25, whose extensions are adapted to enter the alined recesses referred to.

In this latter form of the invention the upper bearing plate is rigidly secured to the heel portion of the shoe by means of nails or other fastening members extending through openings of the upper bearing plate, 11^a, just as previously described in connection with the nails or fastening members, 18, and the construction in Fig. 6 is therefore adapted to operate in substantially the same manner and with equal facility as the construction of Fig. 2. The construction of Fig. 6, as applied to men's shoes, is however somewhat heavier and of greater strength, as will be observed, and a second cushion, 26, is preferably utilized between the upper bearing plate, 11^a, and the heel portion of the shoe proper.

I claim:

1. A shoe heel having a lower tread plate, a pair of upper abutting bearing plates, a cushion between said tread plate and the lower bearing plate, means for securing the upper bearing plate to a shoe, and a single central connecting member joining the several plates and the cushion, upon which the tread plate, cushion, and lower bearing plate are rotatable.

2. A shoe heel having a lower tread plate, a pair of upper bearing plates in movable contact, a cushion between the tread plate and the lower bearing plate, means for rigidly securing the upper bearing plate to a shoe, and a vertical stud, upon which the other plates and the cushion are rotatable, having a lower head, the tread plate being

provided with a counter-bore receiving the head, so as to permit the tread plate to yield vertically with respect to the stud.

3. A shoe heel having a lower tread plate, a pair of upper abutting bearing plates, a cushion between said tread plate and the lower bearing plate, means for securing the upper bearing plate to a shoe, and a single central connecting member joining the several plates and the cushion, upon which the tread plate, cushion, and lower bearing plate are rotatable, said tread plate having a depending flange therearound, for the purpose described.

4. A shoe heel having a lower tread plate, a pair of upper abutting bearing plates, a cushion between said tread plate and the lower bearing plate, means for securing the upper bearing plate to a shoe, and a single central connecting member joining the several plates and the cushion, upon which the tread plate, cushion, and lower bearing plate are rotatable, said bearing plates having relatively engaging annular flanges to reduce their contacting areas.

5. A shoe heel having a lower tread plate and a pair of upper bearing plates in movable contact, a cushion between the tread plate and the lower bearing plate, a vertical connecting stud extending centrally through the several plates and the cushion, having a lower head engaging the tread plate and having its upper end securely fastened to the upper bearing plate, and means to rigidly secure the upper bearing plate to a shoe, all as described.

TOWNSON HAND.
